(57) **CLAIM**

The ornamental design for a light emitting diode lamp, as shown and described.

DESCRIPTION

FIG. 1 is a front view of a lighting emitting diode lamp showing our new design, the rear view, the right side view and the left side view being identical to the front view;

FIG. 2 is a top view thereof;

FIG. 3 is a bottom view thereof; and

FIG. 4 is a perspective view thereof;

FIG. 5 is another perspective view thereof;

FIG. 6 is the other perspective view thereof;

FIG. 7 is a cross-sectional view taken along line 7-7 in FIG. 2;

FIG. 8 is a cross-sectional view taken along line 8-8 in FIG. 2;

and,

FIG. 9 is another cross-sectional view of FIG. 8.
